SAFETY WINDOW AIR ADJUSTER

Filed Feb. 8, 1932

Joseph C. Chalupa, INVENTOR

BY Victor J. Evans & Co.

ATTORNEY

WITNESS:
H. J. Meader

UNITED STATES PATENT OFFICE

JOSEPH C. CHALUPA, OF BERWYN, ILLINOIS

SAFETY WINDOW AIR ADJUSTER

Application filed February 8, 1932. Serial No. 591,729.

This invention relates to a holding device for window sashes, and whereby one or both of the sashes may be partly arranged for the ventilation of a room and wherein the construction is such as to prevent the further opening of either of the sashes and the entrance to the room by unauthorized persons.

A further object is the provision of a means for this purpose which can be easily and quickly attached to the sliding sashes of ordinary windows, to permit of the free sliding of the sashes or for locking or latching either of the sashes to hold the said sash in a partly open position for the ventilation of the room.

15 To the attainment of the foregoing the invention consists in the improvement herein-after described and definitely claimed.

In the drawing:

Figure 1 is a horizontal sectional view 20 through two sliding sashes equipped with the improvement.

Figure 2 is a vertical sectional view approximately on the line 2—2 of Figure 1.

Figure 3 is a substantially similar sectional view 25 but showing the double acting bolt held in a position to permit the free sliding of the sashes.

Figure 4 is a detail sectional view on the line 4—4 of Figure 2.

30 Figure 5 is a detail sectional view on the line 5—5 of Figure 3.

In the drawing the numeral 1 designates a portion of a window casing, between whose beads there are arranged for slidable movement the sashes 2 and 3, respectively. The flanged or beveled lapping edges at the meeting ends of the rails of the respective sashes 2 and 3, adjacent to the parting bead that spaces the said sashes is cut-away to accommodate a rack plate 4 which is fixed on the inner face of the vertical stile of the upper sash 2. The rack may be of any desired length and in fact comprises a flat plate which, at equidistantly spaced intervals, has its outer face thickened by curving the same and the said thickened portions are centrally formed with notches 5.

50 Preferably on the meeting rail of the lower sash 3 and directly opposite what I have termed the rack plate 4 there is fixed a cas-

ing 6 whose outer face is partly open, and in this casing there is pivoted, as at 7, the central portion of a double ended dog 8. The pivot passes through a rounded boss 9 formed on the inner face of the dog, and there is let in the said upper sash a tube 10 that communicates with the casing and there is passed through an opening in the said rail a rod or lever 11 having an outer crank end 12. The inner end of the swingable rod 10 or lever 11 is slotted and has received therein and pivoted thereto, as at 13, the arm or shank 14 of a cam plate 15. The cam 15 is offset from its shank and has an outer widened and flat end which is centrally formed with a round depression 16 to receive therein the boss 9 of the dog when the lever is turned to one position and hold both of the active ends 17 of the said dog in neutral position, that is, to hold the dog out of engagement 70 with the notches 5 in the plate 4. In the tube or sleeve 10 there is a coil pressure spring 18, that contacts with a washer 19 on the lever 11, the said spring forcing the washer 19 against the pivot bolt 13 for the cam.

Normally the lever is in the position disclosed by Figure 3 of the drawing, and the sashes 2 and 3 are free to slide in the window casing. When the lever is turned by gripping the crank end 12 thereof to bring the cam to the position disclosed by Figure 2 of the drawing the said cam will contact with the lever beyond one side of the pivot 7, thus swinging the lever so that one of the active ends 17 thereof will be brought into one of the notches 5. This is accomplished when the upper sash is lowered and permits the upper sash being moved to its closed position but prevents its downward movement. When the upper sash is lowered to admit air into the room the lever is turned to bring the dog 15 to engage with the inner face of the dog at the opposite side of the pivot, which will bring the lower active end 17 of the lever into one of the notches 5. This prevents the lowering of the lower sash. Thus the dog when either of its active ends are in engagement with the notches 5, holds either of the respective sashes but permits the said sashes moving in unison. The notched plate or

rack 4 is only of a length sufficient to admit a desired quantity of air into a room, and it is thought the simplicity of my construction and its advantages will be readily apparent to those skilled in the art when the foregoing has been read in connection with the accompanying drawing so that further detailed description will not be required.

Having described the invention, I claim:

- 10 1. A means for latching upper and lower sashes in a window frame for the admission of fresh air into a room, comprising a rack plate fixed on one of the sashes, a double ended dog carried by the second sash having a central boss and a pivot passing through said boss, a lever passing through said sash and having an outer angle end and spring means influencing the lever in one direction, stop means for limiting such movement of the lever and a cam member secured to and offset from the inner end of the lever and having its outer face notched to normally receive the boss of the double ended dog therein and likewise to contact with the inner face of the dog at points equidistant from the opposite sides of the pivot for swinging either end of said dog to engage with the rack.
- 20 2. A means for holding the sliding sashes of a window casing partly raised or lowered for the admission of air therethrough, comprising a plate fixed to the vertical stile of the upper sash and having spaced enlargements which are notched, a casing fixed in the inner face of the meeting stile of the lower sash and having an open face, a double ended dog having a central rounded boss on its inner end and a pivot carried by the casing for said boss, a tubular member let in said rail from the inner face thereof, a lever slideable through the rail and entering the casing and having an outer cranked end, a cam member having an offset shank received in and secured to the lever, said cam having its outer face widened and formed with a rounded depression to receive the boss of the dog therein when the lever is in one position to permit of the free sliding of the sash and said cam likewise designed when the lever is brought to other positions to contact and to swing the dog to cause either selected end thereof to be received in the notches of the plate and spring means influencing the lever in the direction of the dog.
- 30 3. In testimony whereof I affix my signature.
JOSEPH C. CHALUPA.
